(57) **CLAIM**

The ornamental design for a D-profile door pull, as shown and described.

DESCRIPTION

FIG. 1 is a front view of a D-profile door pull showing my new design;

FIG. 2 is a right side view of the door pull of FIG. 1; FIG. 3 is a top plan view of the door pull of FIG. 1; FIG. 4 is front perspective view of the door pull of FIG. 1; and, FIG. 5 is a partial perspective view of the lower right corner of the door pull of FIG. 1.

The broken line showing of a door in FIGS. 1-3 is included for the purpose of illustrating environmental structure only and forms no part of the claimed design.
